UNITED STATES PATENT OFFICE.

OTTO E. UECKER, OF MILWAUKEE, WISCONSIN.

CLOTHES-HANGER.

1,364,161.

Specification of Letters Patent.

Patented Jan. 4, 1921.

Application filed January 20, 1919. Serial No. 272,144.

To all whom it may concern:

Be it known that I, OTTO E. UECKER, a citizen of the United States, and resident of Milwaukee, in the county of Milwaukee and 5 State of Wisconsin, have invented certain new and useful Improvements in Clothes-Hangers; and I do hereby declare that the following is a full, clear, and exact description thereof.

10 My invention relates to new and useful improvements in clothes hangers for suspending towels, cloths or the corners of blankets and other large pieces, and more particularly to that type adapted to exert 15 a frictional wedge grip on the article held.

It is in general the object of my invention to provide an efficient and readily manipulated device of this character which will lend itself to most economical manu- 20 facture.

A further and important object resides in the provision in a device of this character of an arrangement whereby the weight or stress exerted by an article inserted in the 25 device, serves to increase the gripping action of the jaws of the hanger to prevent accidental detachment of the article held.

A still further object resides in the provision of a hanger device embodying the 30 above features and which may be readily formed of a single length of resilient wire.

With the above and other objects and advantages in view, which will be apparent as the description proceeds, my invention 35 resides in the novel features of construction, combination and arrangement of parts as hereinafter more particularly described and defined by the appended claim.

In the drawing the figure shows an eleva- 40 tional view of a clothes hanger embodying my invention.

Referring now more particularly to the accompanying drawing, I have shown a hanger constituting one embodiment of my 45 invention and formed of a single length of resilient wire. This length of wire is bent at points adjacent its center to form a throat closing portion 5, from the ends of which connecting stretches 6 extend toward each 50 other and divergently with respect to the throat closing portion 5, the end of these connecting stretches being merged into the

ends of jaw stretches 7 which extend transversely of the throat closing portion 5 and which define a throat for receiving the article to be held, these jaw stretches being articulately divergent from the throat closing portion 5 whereby the restricted end of the throat is disposed adjacent said portion 5 and at their ends remote from the restricted 60 portion of the throat the jaw stretches are spaced apart a sufficient distance to permit free insertion of any article to be held in the throat.

From these end portions of the jaw 65 stretches, the ends 8 of the wire are directed together and terminate in interlocked eyes 9, one of which is relatively large for engagement with the eye 10 of a suspension screw or with any other suspension member. 70

An exceedingly simple and readily formed device has thus been provided which will efficiently hold clothing or other articles in such manner that the gripping action is increased upon increase of stress tending to 75 displace the article in the direction of the closed portion of the throat. This action is effected by engagement of the article against the throat closing wire portion 5, pressure exerted thereon obviously tending 80 to draw the jaw stretches 7 together to increase the clamping action.

By bending the throat closing stretch 5 of the wire in a plane substantially at right angles to the plane of the jaw portions 7, 85 said jaw portions may be adjusted toward and away from each other for efficient gripping action on various thicknesses of cloth which it is desired to hold thereby.

What is claimed is:

A hanger of the class described formed of a single length of wire bent to provide an intermediate stretch, return portions bent at the ends of said intermediate stretch to form relatively large loops, jaw stretches extending divergently from said return portions and crossing the central portion of the intermediate stretch, the said loops being elongated transversely of the jaw portions to increase resiliency of the latter, connecting suspension portions at the ends of the gripping portions of the jaw stretches, an eye formed on the free end of one suspension portion and slidably receiving the free end 95 100

of the other, and an eye formed on the said other suspension portion and loosely embracing the first mentioned eye whereby the jaw stretches may have freedom of movement, pressure exerted against the intermediate stretch by an article disposed between the gripping portions of the jaw stretches

operating to draw said gripping portions together.

In testimony that I claim the foregoing I 10 have hereunto set my hand at Milwaukee, in the county of Milwaukee and State of Wisconsin.

OTTO E. UECKER.
